GRINDING APPARATUS

Erik Stephansen, Bestun, Oslo, Norway, assignor
to Papirindustriens Forskningsinstitutt, Oslo,
Norway

Application April 5, 1949, Serial No. 85,690
In Norway December 17, 1946

1 Claim. (Cl. 241—199)

1

The present invention relates to a grinding apparatus for fibrous materials for instance cellulose, of the type which comprises two grinding elements one of which, the so called roll, has the shape of a body of rotation for instance a cylinder or a cone which conveniently is provided with knives along the circumference and is rotatably mounted on its axis. The other grinding element has the shape of a case, which encloses the roll and which is likewise rotatably mounted on its axis, the grinding being effected between the roll and the inner wall of the case co-operating with the roll.

The invention relates to an embodiment of such an apparatus, which is particularly convenient for use in laboratories for performing grinding tests. For this purpose the apparatus comprises a vertically arranged spindle, two sleeves mounted on the spindle each of which sleeve carries two horizontal arms arranged in opposite directions, the arms of one of the sleeves at their oppositely directed ends carry respectively a bearing for a grinding roll mounted on a vertical axis, and a motor which serves to drive the said roll, whereas the arms on the other sleeve at their oppositely directed ends carry respectively a bearing for a rotatably mounted case adapted to enclose the said roll during the grinding operation, and a motor adapted to rotate the said case. At least one of the sleeves is conveniently rotatably mounted on the spindle in such a way that the roll and the case are reciprocally adjustable in radial direction. The apparatus comprises for this purpose a device by means of which a determined grinding pressure can be maintained.

By this construction there is obtained a series of factors which influence the grinding operation that can be adjusted independently of each other such as, for instance, the speed of rotation of the case and the roll as well as the relative speed of periphery of these two elements. Furthermore the pressure of grinding can be adjusted and kept constant independently of the turning moments of the motors. Under the influence of the centrifugal force, the material takes the shape of an annular layer on the inside of the wall of the case, which layer rotates with the case. As a consequence of this forced rotation the apparatus can grind material of any consistence.

A feature of the apparatus according to the invention consists in that at least one of said sleeves is arranged in such a way that it can be lifted and lowered on the spindle. In this way

the roll and the casing may easily be removed from each other axially.

In the following the invention will be described more in detail in connection with the drawing, which illustrates an embodiment of an apparatus according to the invention. Figure 1 is a side view of a grinding apparatus according to the invention ready for use, partly in section.

Figure 2 is a section on the line II—II in Figure 1.

Figure 3 is a plan view corresponding with Figure 1.

1 is a base plate carrying a vertical spindle 2. Close to the upper end of the spindle is rotatably mounted a sleeve 3. This is provided with one laterally projecting horizontal arm 4 at the left end of which is rotatably mounted an axle 5 parallel with the spindle. To the lower end of the axle is secured the grinding roll 6 which along its periphery is provided with teeth 7.

To the upper end of the axle 5 is secured a pulley 8.

25 The sleeve 3 is, in the opposite direction to the arm 4, furthermore provided with an arm 9 which carries a motor 10.

The axle of the motor is arranged parallel with the spindle and is, at its upper end, provided with a pulley 11 which by means of a rope or a belt 12 is drivingly connected with the pulley 8.

30 At a distance below the sleeve 3, on the spindle, there is mounted another sleeve 13 which, by means of a device to be described later, can be lifted and lowered on the spindle but otherwise by means of a key 13a is prevented from turning on the spindle. The sleeve 13 is, like the sleeve 3, provided with oppositely directed extending arms 14 and 23 of which the last men-

35 tioned carries a motor 24. At the left end of the arm 14 is rotatably mounted a vertical axle 15, which at its upper end is provided with a tapered head 16 fitting into a tapered bore in a downwardly projecting hub 17 on the under

40 side of a casing of grinding 18, which in the working position of the apparatus encloses the roll 6. The shaft 15 and the head 16 can be firmly secured to the grinding case 18 and the hub 17 by means of the nut 19. 20 is a cover for the case 18, which is open at the top. The cover is provided with a central opening 21 of diameter so that the axle can be moved laterally in the opening 21.

45 At its lower end the shaft 15 is provided with a pulley 22.

As already mentioned the sleeve 13 is furthermore provided with an arm 23 extending oppositely to the arm 14 and which carries a motor 24. The vertically arranged axle of the motor is at its lower end provided with a pulley 25 which by means of a rope or a belt 26 is in driving connection with the pulley 22.

On its lower part the spindle 2 is provided with teeth 27. To the sleeve 13 is secured a casing 28 in which a cylindrical body 29 is rotatably mounted, which body is provided with teeth engaging the teeth 27. The body 29 is furthermore provided with a second set of teeth 30 which engages worm threads 31 on the shaft 32 which is likewise mounted in the casing 28 and crosses the body 29. The screw 31 can be rotated by means of a cranked handle or hand-wheel 33. The casing 28 respectively the sleeve 13 is at 34 provided with a slit through which a screw 35 is extending. This screw is at one end provided with a knob or a curled edge 36 and when screwed down serves the purpose of clamping the casing 28 or the sleeve 13 to the spindle in adjusted position.

Besides the arms 4 and 9 the sleeve 3 is provided with a third arm 37 which, in the embodiment presented in the drawing, extends perpendicularly to the first mentioned arms. The arm 37 is at its free end provided with a downwardly extending nose 38 for co-operation with the upper end of an arm 39 which is rotatably mounted on a stud 40 secured to the spindle. The arm 39 has a prolonged approximately horizontally extending arm 41 which at its free end is arranged for being loaded with one or more loads 42. The arms 39 and 41 are furthermore provided with a downwardly projecting arm 43 which can co-operate with a cam 44 which by means of a handle 45 can be rotated on the stud 46.

The apparatus is used in the following way:

When a portion of material has to be fed into the grinding case, the case has to be lowered from the position shown in the drawing. Before the case can be lowered the grinding roll 6 has to be withdrawn from engagement with the case.

This is performed by turning the handle 45 and thereby the cam 44 about 90° towards the right. The cam 44 will thereby push the arm 43 and turn same as well as the arms 41 and 39 counterclockwise. The nose 38 is thereupon disengaged from the arm 39 and the sleeve 3 with the arms 4 and 9 can be turned clockwise as seen in Figure 3. This turning may be performed automatically by use of a spring. Now the screw 36 is slackened and thereupon the handle 33 is turned whereby the body 29 will be rotated by engagement between the worm threads 31 and the teeth 30. The teeth on the body 29, not shown in the drawing, which are in engagement with the teeth 27 will thereby bring about the lowering of the sleeve 13 and the members secured to same. The grinding case 18 is consequently lowered while the cover 20 will remain upon the

grinding roll 6. If so desired the case may now by screwing out the nut 19 be separated from the axle 15, freed from ground material and fed with a fresh portion of a mass to be ground.

Thereupon the case is again secured to the head 16 on the axle 15 and is, by turning the handle 33 in opposite direction, lifted to the position shown in the drawing.

Now both motors 10 and 24 are started. The motors may either be constructed for fixed speeds of revolutions or be so constructed that the number of revolutions can be regulated. The construction is made in such a way that the grinding roll 6 and the case 18 rotate in the same direction but with different speed of periphery. When the motors have been started the handle 45 is turned back to the position shown in the drawing so that the sleeve 3 by the effect of the load 42 will be turned to the position shown in Figure 3. The teeth 7 of the grinding roll 6 will hereby be pressed against the inner side of the casing 18 with a fixed pressure which may be regulated as desired by varying the load 42.

I claim:

25 Grinding apparatus of the kind described, comprising a vertical spindle, two horizontal arms turnably mounted relatively to each other on said spindle intermediate their ends, two motors, one carried by each one of said arms at one end thereof, a grinding roll rotatably mounted on one of said arms at the end opposite said motor carried by said arm, a case rotatably mounted on the second of said arms at the end opposite the motor carried by said arm and adapted to enclose said grinding roll during operation, belt-and-pulley connections between each of said motors and said grinding roll and said case respectively, a third arm secured to said arm carrying said grinding roll and extending substantially perpendicular to said arm, a horizontally extending arm pivotally mounted on said spindle and having a projection thereon contactable with said third arm and weight means carried at the free end of said horizontally extending arm, said horizontally extending arm being adapted by co-action between said projection and said third arm due to said weight for adjusting grinding pressure between said grinding roll and said case by varying said weight.

50 ERIK STEPHANSEN.
